CLAIM

The ornamental design for a torso garment, as shown and described.

DESCRIPTION

The FIG. 1 is a front view of a torso garment, shown on an environmental human depiction in accordance with the claimed design;

FIG. 2 is a front view of the design of FIG. 1 in an open configuration;

FIG. 3 is a perspective view of the design of FIG. 1 in an open, loose configuration;

FIG. 4 is a front view of the design of FIG. 1 in a closed configuration;

FIG. 5 is a left side view of the design of FIG. 1, the right side view being a mirror image thereof;

FIG. 6 is a rear view of the design of FIG. 1;

FIG. 7 is a top view of the design of FIG. 1, shown in a partially open configuration; and,

FIG. 8 is bottom view of the design of FIG. 1, shown in a partially open configuration.

The broken lines in the figures represent environment in which the claimed design may be embodied, and which form no part of the claimed design.

The surface shade lines in the figures show contour, and do not indicate any surface ornamentation, opacity, or translucency.
